UNITED STATES PATENT OFFICE.

CARL BIERNAT, OF GLASFORD, ILLINOIS.

MINING-DRILL.

1,354,944.

Specification of Letters Patent.

Patented Oct. 5, 1920.

Application filed May 8, 1920. Serial No. 379,824.

To all whom it may concern:

Be it known that I, CARL BIERNAT, a citizen of Poland, residing at Glasford, in the county of Peoria and State of Illinois, have 5 invented certain new and useful Improvements in Mining-Drills, of which the following is a specification.

The primary object of the invention is the provision of a hand operated drilling device adapted for drilling blast holes and the like, the device being simple and strong 10 in construction, readily operable by a single workman and requiring but slight attention or adjustment.

15 A further object of the invention is the provision of a drilling machine that is readily taken apart for repairs as well as disassembled for changing the position of the machine from one place to another, provision being made for driving a bit substantially horizontally while lubricating means and driving connections are also provided.

With these general objects in view the 20 invention consists in the novel form, combination and arrangement of parts hereinafter more fully described, illustrated in the accompanying drawings and pointed out in the appended claims.

30 In the drawings like reference characters indicate corresponding parts throughout the several views, and

Figure 1 is a top plan view of the invention with a bit positioned for use and parts 35 broken away,

Fig. 2 is a side elevation thereof with the crank removed,

Fig. 3 is a vertical longitudinal sectional view taken upon line III—III of Fig. 1,

40 Fig. 4 is a front elevation of the same,

Figs. 5 and 6 are vertical transverse sectional views taken upon lines V—V and VI—VI respectively of Fig. 1, and

Fig. 7 is an elevational view of the attaching end of the crank.

Referring more in detail to the drawings, my invention broadly comprises a horizontally arranged cylinder consisting of two parts 10 and 11 connected together by 50 hinges 12, an operating screw 13 longitudinally positioned through the cylinder and adapted for operation in the manner hereinafter set forth whereby a bit 14 detachably mounted upon either end or shank 55 of the screw may be driven into and removed from the work. A gear 16 has a hub

17 journaled in the forward end of the bore 18 of the cylinder while a flange 19 upon the hub revolves in an annular groove 20 of the bore 18. In this manner, the gear 16 is 60 journaled upon the forward end of the cylinder when the sections 10 and 11 thereof are closed, a retaining latch 21 being provided for normally maintaining said sections in closed relations. A forward extension 22 of the gear 16 is journaled in a saddle 23 of the front support 24 of the device while a rear support 25 supports the rear end of the cylinder by means of lugs 26 projecting from the section 11 being 70 seated in the heads 27 of the rear support 25.

A shaft 28 projects from one side of the cylinder section 11 being suitably connected thereto as by the swivel 29, a sleeve 30 75 being journaled upon the shaft 28 with a pinion 31 in constant mesh with the gear 16. A head 32 upon the outer end of the shaft 28 retains the sleeve 30 thereon while a lubricating port 33 through the sleeve 30 80 is normally closed by a spring pressed cap 34.

The screw 13 being threaded through the threaded portion 35 of the cylinder bore, the operation of boring by means of the bit 14 85 will be at once apparent. A crank 36 is adapted for detachable connection with the sleeve 30, spaced circular openings 37 and 38 being provided through the crank so that the latter is easily positioned upon the sleeve 90 30. A recess 39 in the sleeve 30 has an entrance slot 40 at the end of the sleeve permitting an inwardly projecting rib 41 carried by the handle 36 within the openings thereof to be slidably positioned through the 95 slot 40 into the recess 39 for engaging the rib 41 with either of the opposite walls 42 of said recess when turning the crank 36 for revolving the said sleeve 30. The sleeve 30 and its pinion 31 are revolved in this manner in either direction desired by means of the crank 36, the gear 16 being turned by said pinion 31 which feeds the screw 13 through the threaded bore 35 of the cylinder 10, carrying the bit 14 rotarily into the work 105 during the boring operation while a reverse movement of the crank 36 withdraws the bit 14. The shank 15 upon either end of the screw 13 may be employed for mounting a bit thereon while it will be apparent that 110 any securing means desired may be employed for detachably holding the bit 14

upon the shank. The length of the operative portion of the crank 36 is altered by employing the different openings, the opening 38 when positioned upon the sleeve 30 5 providing a shorter length of throw for the crank than when the end opening 37 is employed. A serviceable and strong drill is provided for boring into any desired object such as a bank of coal, the shaft 28 being 10 lubricated through the port 33 while the bore 18 inwardly of the hub 17 receives lubricating grease for the screw 13 when the top section 10 of the cylinder is opened.

While the form of the invention herein 15 set forth is believed to be the preferable embodiment thereof, it will nevertheless be understood that minor changes may be made therein without departing from the spirit and scope of my invention.

20 What I claim as new is:—

1. A drill comprising a cylinder having a lower section and an upper section hinged thereto, securing means for the sections when closed, a gear journaled at one end of the 25 cylinder adapted for removal when the cylinder is open, a support having a saddle portion adapted for journaling the hub of the gear therein when the device is assembled, another support at the opposite end 30 of the lower section, and an operating screw slidable through the gear and threaded through the cylinder.

2. A drill comprising a cylinder having a lower section and an upper section hinged 35 thereto, securing means for the sections when closed, a gear journaled at one end of the cylinder adapted for removal when the cylinder is open, a support having a saddle portion adapted for journaling the hub of 40 the gear therein when the device is assembled, another support at the opposite end of the lower section having bit receiving shanks

at its opposite ends, a sleeve journaled at right angles to the lower section of the cylinder, a pinion upon said sleeve meshing 45 with said gear, and a removable operating crank for the sleeve.

3. A drilling machine comprising a two-part cylinder, a screw axially threaded therethrough with a bit receiving shank at 50 each end thereof, a gear having a hub portion journaled in the cylinder and also having an outer extension with a bore for the gear member through which said screw slidably extends, a support for one end of the 55 machine attached to one section of the cylinder, and a support for the opposite end of the machine in which the extension of the gear is seated for turning.

4. A drilling machine comprising a two-part cylinder, a screw axially threaded therethrough with a bit receiving shank at 60 each end thereof, a gear having a hub portion journaled in the cylinder and also having an outer extension with a bore for the 65 gear member through which said screw slidably extends, a support for one end of the machine attached to one section of the cylinder, a support for the opposite end of the machine in which the extension of the gear 70 is seated for turning, a laterally projecting shaft swiveled to the lower section of the cylinder, a head upon the outer end of the shaft, a pinion having a hub in the form of a sleeve journaled upon the shaft with a 75 lubricating port in the side thereof, the pinion being in mesh with the gear when the device is assembled for use, and operating means for the machine detachably connected to said hub of the pinion whereby the latter 80 is adapted to revolve during operation.

In testimony whereof I affix my signature.

CARL BIERNAT.
